DESIGN FOR AN APPLICATOR

George Bennett, New York, N. Y., assignor to Raphael L. Roston, Queens County, N. Y.

Application June 28, 1940, Serial No. 93,313

Term of patent 14 years

To all whom it may concern:

Be it known that I, George Bennett, a citizen of Russia, residing at New York, in the county of New York and State of New York, have invented a new, original, and ornamental Design for an Applicator, of which the following is a specification, reference being had to the accompanying drawing, forming part thereof.

In the drawing

Fig. 1 is a front elevational view of an applicator showing my new design;

Fig. 2 is a top plan view thereof on a slightly enlarged scale; and

Fig. 3 is a bottom plan view of Fig. 2.

I claim:

The ornamental design for an applicator, as shown.

GEORGE BENNETT.
